UNITED STATES PATENT OFFICE.

GUY W. BLACKBURN, OF ELGIN, ILLINOIS.

BURNISHING MACHINE.

Application filed December 9, 1925. Serial No. 74,235.

My invention relates to a burnishing and buffing and polishing and scratch brushing machine and has for particular purpose a provision of a machine adapted to burnish, buff, scratch brush or polish articles of metal or other substances, the contours of which are irregular. One purpose of my device is to provide a machine of the class described wherein the means which engage the work automatically conform to the level of that part of the work with which they are in contact. Another object is the provision of a burnishing, buffing, polishing or scratch brushing machine wherein the work engaging elements are adapted to rise and override upper projections from the level of the work and are adapted to return to their normal low level when opposed with two lower portions of the work. Other objects will appear from time to time throughout the specification and claims.

I illustrate my invention more or less diagrammatically in the accompanying drawings wherein—

25 Figure 1 is a side elevation of my device; Figure 2 is a section on the line 2—2 of Figure 1;

Figure 3 is a section on the line 3—3 of Figure 1;

30 Figure 4 is a section on the line 4—4 of Figure 5;

Figure 5 is a section on the line 5—5 of Figure 1;

35 Figure 6 is a section on the line 6—6 of Figure 5;

Figure 7 is a detail of a variant form of work engaging member;

Figure 8 is a plan view of a variant form of my device;

40 Figure 9 is a section on the line 9—9 of Figure 8;

Figure 10 is a section on the line 10—10 of Figure 9;

45 Figure 11 is a section on the line 11—11 of Figure 9; and

Figures 12 and 13 are variant forms of burnishing members.

Like parts are indicated by like characters throughout the specification and drawings.

50 Referring to Figures 1 and following, A is any suitable base or work supporting member diagrammatically illustrated. Up-

wardly projecting from it are the supporting members A¹ which are connected by the 55 intermediately positioned transverse plate A² and by the upper transverse plates A³ A⁴ which are spaced slightly apart.

Aligned along said plates are a plurality of pairs of rotating shafts or spindles B B¹. 60 Each such spindle passes through a pinion B² or B³, such pinions being all in mesh and being rotated by a gear B⁴ upon the spindle or shaft B⁵ which may be rotated, for example, by the chuck B⁶. Each spindle B or B¹ 65 is slidably mounted in relation to such pinion B² or B³, such pinions being contained between the transverse plates A³ A⁴. The spindles are, however, keyed or held against relative rotation in relation to said pinions, 70 for example, by the keys B⁷. Preferably the fit of spindle in pinion is sufficiently loose to permit a certain tilting of the spindle as shown, for example, in Figure 5. The spindles are limited as to their downward movement by the stop collars B⁸ adjustably mounted thereon.

Each such spindle B or B¹ is provided with a lower screw threaded or worm portion C or C¹, the spindles of each pair being 80 oppositely threaded or pitched. The screw threaded or worm portions which are shown in cross section in Figure 4, are hollow as at C², a hollow sleeve C³ being held in position therein, for example, by the set screw C⁴. 85 C⁵ is a U-shaped wire headed as at C⁶ and passing through the hollow of the sleeve C³ and freely rotatable in relation thereto. The wire C⁵ serves as a stiffener or guide or reinforcement for a flexible member for example, a closely twisted spiral spring C⁷ which is held against rotation in relation to the sleeve C³ and the spindle itself. It will be understood that the ends of the wire C⁵ 90 are identical, a wire of this type being associated with each pair of spindles, the wire being preferably sufficiently flexible to permit the lower bend of the U to conform to the shape of the work flattening out, for example, as shown in Figure 6. Referring to

Figure 12 I illustrate a form of spring plunger comprising the wire or member C¹⁰ and the spring C¹¹ about which the diameter of the coils of the spring increase as at C¹² at the work engaging portion of the U. Figure 13 illustrates a further variant form in

which a spring C^{20} is rotated about a horizontal axis for example by the opposed pins or spindles C^{21} .

Mounted about each pair of spindles is a guide block D , perforated as at D^1 D^1 to permit the passage of the spindles, the perforations being of sufficient diameter to permit free rotation of the spindles. These guide blocks are threaded along a plurality of guide wires D^2 , there being a pair of guide wires for each block, and as many pairs of guide wires as there are blocks as will be clear from Figures 5 and 6. A guide wire is secured to each side of each block, as at D^3 , for example, by an outwardly projecting lug on the side of the block. The guide wires pass through vertical guide standards D^4 , the outwardly projecting ends being provided with adjustable abutments D^5 between which and the standards D^4 are compressed spiral springs D^6 .

The transverse guide plate A^2 is apertured to permit a passage of the spindles, and is so positioned in relation to the spindles as always to receive the screw threaded or worm portion of such spindles. The spindles are of such diameter that when the spindles are in vertical position they do not engage the aperture walls. The walls, however, are screw threaded to conform to the screw threading or worms of the spindle.

Referring to Figures 8 and following, I illustrate a variant form of my device in which I employ a plurality of rows of single spindles. Therein the drive shaft E and its pulley E^1 actuate an endless belt E^2 which passes about a plurality of pulleys E^3 positioned between the upper transverse plates A^3 and A^4 . The single spindles E^4 are slidably mounted in said pulleys but are provided with splines E^5 to prevent rotation therein. The guide blocks E^6 are identical with those above described and are guided by guide wires E^7 similar to the guide wires D^2 . Each guide block E^6 , however, has but a single aperture and controls a single spindle. Each spindle is provided at its lower end with any suitable buffing, grinding or polishing element. I illustrate, however, in Figure 7 a brush G which may be of wire or bristle, contained in a collar G^1 apertured as at G^2 to receive the lower end of the spindle, to which it is secured by the set screw G^3 . Referring to Figure 11, I illustrate a fibrous buffing head H , centrally apertured as at H^1 to permit access to a screw H^2 , whereby its holding plate H^3 is secured to the lower end of the solid spindle H^4 . H^5 is any suitable stop to prevent relative rotation of the buffing member H and its supporting plate H^3 .

It will be realized that whereas I have illustrated a practical and operative device, nevertheless many changes may be made in the size, shape, number and disposition of

parts without departing from the spirit of my invention and that I wish my drawings to be taken as in a practical sense illustrative or diagrammatic rather than as limited to the specific structures therein described and shown.

The use and operation of my invention are as follows:

Broadly stated one of the most important features of my device is the diagrammatic adjustment of the rotating spindles to the height of the work upon which they operate. I obtain this effect by keying the spindles in their driving pinions or pulleys to permit free axial movement and to allow a certain tilting. The stops B^8 which are adjustable, limit the downward movement of the spindles to some predetermined form. When the spindles are operating upon a piece of work, the thrust being directly downward upon the work, they are aligned by the guide blocks D or E^6 , being thereby constrained to a vertical position. When in such vertical position, they are out of contact with the screw threaded walls of the apertures in the plate A^2 and the worm portion of each spindle is out of contact with any opposed worm or screw threaded member. The spindles therefore drop either to the level limited by the stop B^8 or to that level wherein the spindle or the working member at its end contacts the work. Thus if a flat plate is placed on the base A , the thickness being greater than the minimum distance between the working members on the spindles or upper surface of the base A they will operate on the flat surface of the plate and will be maintained in vertical position by the guide blocks and by the balance springs at the ends of the guide wires D^6 .

However, if as shown in Figure 5, a member of irregular contour or of thickness greater than the minimum distance between the working members and the base is inserted, its lateral pressure against the spindles or their working members frees them against the resistance of the spiral springs D^6 and holds the worm portions in engagement with the opposite screw threaded portions of the apertures in the plate A^2 . Since the spindles are in constant rotation, they are forthwith lifted until they clear the portion of the work which constrains them to a laterally tilted position. They then spring back into vertical position owing to the compression of the springs D^6 , and upward movement ceases and the downward normal pressure of the weight of the spindle holds the working member in its normal working engagement with the face of the work.

Referring particularly to the form of Figures 1 and following I employ for burnishing a plurality of pairs of spindles, each such pair being connected by a U-shaped

non-rotating wire and by a spiral spring which rotates about the wire, the wire serving as guide and reinforcement to the spring. The opposite spindles of each pair 5 rotate in opposition and the effect is to rotate the springs C' which serve as burnishing members.

Referring more particularly to the form of Figures 8 and following, I show a 10 variant drive by means of an endless belt E² instead of through pinions and gears. In addition to the change in the driving mechanism I employ single spindles instead of spindles arranged in pairs and I mount at 15 the end of each spindle any appropriate buffing or polishing member, for example, a fiber pad H or a brush G.

Referring to Figures 5, 6, 12 and 13, I illustrate a particularly efficient form of 20 burnishing member consisting of a guide wire or member about which is rotated a finer coiled wire or spring. The rotation of the spring, when the burnishing member is applied to the work to be burnished has the 25 effect of drawing the wires or coils forming the springs with great rapidity across the surface of the substance being burnished, in response to the rotation of the spring. A similar effect may be obtained in the form 30 of Figure 13, wherein a flat flexible spring coil is employed. The guide member C⁹ or C¹⁰ is preferably sufficiently flexible to conform to the work, thus enabling me to burnish irregularly formed objects.

35 I claim:

1. In a device of the class described, a 40 vertically disposed rotating element and means for rotating it, a work engaging member at the lower extremity of such element and means for axially moving said element automatically in response to irregularities of the contour of the work.

2. In a device of the class described, a 45 vertically disposed rotating element and means for rotating it, a work engaging member at the lower extremity of such element and means for axially moving said element automatically in response to lateral displacement of the element.

50 3. In a device of the class described, a vertically disposed rotating element and means for rotating it, a work engaging member at the lower extremity of such element and means for axially moving said element 55 automatically in response to lateral tilting of the element.

4. In a device of the class described a 60 plurality of vertically disposed rods and means for rotating them, said rods being mounted to permit free axial movement during such rotation, and means for lifting said rods in response to such rotation, and in automatic response to variations in the contour of the work.

65 5. In a device of the class described, a

plurality of vertically disposed rods and means for rotating them, said rods being mounted to permit free axial movement during such rotation, and means for lifting said rods in response to such rotation, and in 70 automatic response to variations in the contour of the work, comprising screw threads on said rods and a member about said rods being provided with a screw threaded aperture of greater diameter than the rods. 75

6. In a device of the class described, a plurality of vertically disposed rods and means for rotating them, said rods being mounted to permit free axial movement during such rotation, and means for lifting said rods in response to such rotation, and in automatic response to variations in the contour of the work comprising screw threads on said rods and a member about 80 said rods being provided with a screw threaded aperture of greater diameter than the rods, and means for normally centering said rods in said apertures out of contact with the screw threaded walls thereof. 85

7. In a device of the class described, a 90 vertically disposed rod, a driving member to which said rod is keyed, the rod being axially movable in relation to the driving member, means for imparting a driving movement to said driving member, a worm portion on said rod, an apertured member through which said worm portion passes, such aperture being of greater diameter than the worm, the walls thereof being formed to conform to such worm, and means for 95 normally holding said worm out of contact with said walls. 100

8. In a device of the class described, a 105 vertically disposed rod, a driving member to which said rod is keyed, the rod being axially movable in relation to the driving member, means for imparting a driving movement to said driving member, a worm portion on said rod, an apertured member through which said worm portion passes, such aperture being of greater diameter than the worm, the walls thereof being formed to conform to such worm, and means for 110 normally holding said worm out of contact with said walls, comprising an apertured guide yoke about said rod and means for normally holding it in centering position. 115

9. In a device of the class described, a 120 vertically disposed rod, a driving member to which said rod is keyed, the rod being axially movable in relation to the driving member, means for imparting a driving movement to said driving member, a worm portion on said rod, an apertured member 125 through which said worm portion passes, such aperture being of greater diameter than the worm, and means for normally holding said worm out of contact with said walls comprising an apertured guide yoke about 130

said rod and yielding means for normally holding it in centering position.

10. In a device of the class described, a vertically disposed rod, a driving member to which said rod is keyed, the rod being axially movable in relation to the driving member, means for imparting a driving movement to said driving member, a worm portion on said rod, an apertured member through which said worm portion passes, such aperture being of greater diameter than the worm, the walls thereof being formed to conform to such worm, and means for normally holding said worm out of contact with said walls, comprising an apertured guide yoke about said rod, thrust wires associated with said guide yoke, fixed spring abutments through which said wires pass, abutments on the ends of said wires and yielding means compressed between said fixed abutments and the abutments on said wires.

11. In a device of the class described, a plurality of vertically disposed rods, driving members to which said rods are keyed and means for driving them in unison, each rod being axially movable in relation to its particular driving member, worm portions on said rods, an apertured member through which said worm portions pass, such apertures being of greater diameter than the worms, the walls thereof being formed to conform to such worms and means for normally holding said worms out of contact with said walls.

12. In a device of the class described, a plurality of vertically disposed rods, driving members to which said rods are keyed and means for driving them in unison, each rod being axially movable in relation to its particular driving member, worm portions on said rods, an apertured member through which said worm portions pass, such apertures being of greater diameter than the worms, the walls thereof being formed to conform to such worms and means for normally holding said worms out of contact with said walls, comprising apertured guide yokes about said rods and means for normally holding them in centering position.

13. In a device of the class described, a plurality of vertically disposed rods arranged in longitudinal alignment, driving members to which said rods are keyed and means for driving them in unison, each rod being axially movable in relation to its particular driving member, worm portions on said rods, an apertured member through which said worm portions pass, such apertures being of greater diameter than the worms, the walls thereof being formed to conform to such worms and means for normally holding said worms out of contact with said walls.

14. In a device of the class described, a plurality of vertically disposed rods ar-

ranged in longitudinal alignment, driving members to which said rods are keyed and means for driving them in unison, each rod being axially movable in relation to its particular driving member, worm portions on 70 said rods, an apertured member through which said worm portions pass, such apertures being of greater diameter than the worms, the walls thereof being formed to conform to such worms and means for normally holding said worms out of contact with said walls, comprising apertured guide yokes about said rods and means for normally holding them in centering position including thrust wires associated with said 80 yokes, fixed spring abutments through which said wires pass, abutments on the ends of said wires and yielding means pressed between said fixed abutments and the abutments on said wires.

15. In a device of the class described, a plurality of vertically disposed rods, arranged in pairs, driving members to which said rods are keyed and means for driving them in unison, the rotational direction of the rods and driving members of each pair being opposed, each rod being axially movable in relation to its particular driving member, worm portions on said rods, an apertured member through which said worm portions pass, such apertures being of greater diameter than the worms, the walls thereof being formed to conform to such worms and means for normally holding said worms out of contact with said walls.

16. In a device of the class described, a plurality of vertically disposed rods, arranged in pairs, driving members to which said rods are keyed and means for driving them in unison, the rotational direction of the rods and driving members of each pair being opposed, each rod being axially movable in relation to its particular driving member, worm portions on said rods, an apertured member through which said worm portions pass, such apertures being of greater diameter than the worms, the walls thereof being formed to conform to such worms and means for normally holding said worms out of contact with said walls, a U-shaped wire associated with each pair of rods, the ends thereof engaging such rods and in rotational relation therewith, a flexible member surrounding said wire and engaging the ends of said rods and in non-rotational relation therewith.

17. In a device of the class described, a plurality of vertically disposed rods, arranged in pairs, driving members to which said rods are keyed and means for driving them in unison, the rotational direction of the rods and driving members of each pair being opposed, each rod being axially movable in relation to its particular driving member, worm portions on said rods, an

- apertured member through which said worms pass, such apertures being of greater diameter than the worms, the walls thereof being formed to conform to such worms and means for normally holding said worms out of contact with said walls, a U-shaped wire associated with each pair of rods, the ends thereof engaging said rods and in rotational relation therewith, a spiral spring 5
10 rounding said wire and engaging the ends of said rods and in non-rotational relation therewith.
18. A burnishing tool comprising a close coiled spiral spring and means for rotating it, and a flexible reinforcing member about which such spring rotates.
19. A burnishing tool comprising a close coiled spiral spring and means for rotating it, and a U-shaped flexible wire reinforcing 15
20 member about which such spring rotates.
20. A burnishing tool comprising a close coiled spiral spring and means for rotating it, and a reinforcing member about which such spring rotates, said spring comprising 25 portions of varying diameter.
21. A burnishing tool comprising a U-shaped flexible wire reinforcing member, a

close coiled spiral spring about such reinforcing member and means, secured to each end thereof, for rotating it.

22. A burnishing tool comprising a close coiled spiral spring and means for rotating it, and a U-shaped flexible wire reinforcing member about which such spring rotates, the spiral spring increasing in diameter from its ends to the middle portion about the bottom of the U.

23. The process of burnishing which comprises imparting a rapid rotation to a flexible spiral spring, and passing the work to be burnished across the axis of rotation of said spring in a plane perpendicular thereto and in contact with the spring.

24. The process of burnishing which comprises imparting a rapid rotation to a flexible spiral spring, and passing the work to be burnished across the axis of rotation of said spring in a plane perpendicular thereto and in contact with the spring, and pressing said spring downwardly against the work.

Signed at Chicago, county of Cook, and State of Illinois, this 5th day of December, 1925.

GUY W. BLACKBURN.
